LOCKING BRACE FOR FOLDING TABLE LEGS

John B. Adler, Lincoln Park, Mich., assignor to
Shwayder Brothers, Ecorse, Mich., a corpora-
tion of Colorado

Application January 3, 1949, Serial No. 68,931

2 Claims. (Cl. 311—99)

1

This invention relates to card table constructions, and more particularly to a novel table-leg supporting and securing device.

It is the object of the present invention to provide a novel leg mounting for a card table including a leg supporting bracket within which the leg is pivotally mounted, together with a pivotal link joined to the table frame at one end and retainingly engaging the table leg at its other end for securing the same in open position.

It is the further object of this invention to provide a control link pivotally joined to the table frame and having a sliding connection with the pivotal leg together with means for retainingly securing said leg in open position.

It is the further object of this invention to provide in such a linkage a slotted portion therein for retainingly receiving a pin, said slotted portion terminating in a circular opening of increased diameter for lockingly receiving a shoulder portion of said pin when the table leg is positioned at right angles to the plane of the table frame.

It is the further object of this invention to pivotally mount said link to the table frame in a biased relation thereto so that said link is under tension when guidably receiving the locking device so that when the leg is in fully open position said link will resiliently snap into locking relation with said locking device.

These and other objects will be seen from the following specification and claims in conjunction with the appended drawing in which:

Figure 1 is a fragmentary plan view of a card table with the cover therefor broken away to illustrate one form of pivotal mounting for the table leg.

Figure 2 is a similar view illustrating a slightly different form of pivotal mounting for the table leg and including a linkage for securing the same in fully opened position.

Figure 3 is an elevational section taken on line 3—3 of Fig. 2.

Figure 4 is a transverse elevational section taken on line 4—4 of Figure 3.

Figure 5 is a fragmentary elevational view of the outer lower end portion of the leg engaging link shown in Figure 4, being a section on line 5—5 of Figure 3.

Figure 6 is a section taken on line 6—6 of Figure 5.

Figure 7 is a view similar to Figure 5 but positioned corresponding to the dotted line indication of said link in Figure 4 where the leg is partially closed; and

2

Figure 8 is a sectional view taken on line 8—8 of Fig. 7.

It will be understood that the above drawing illustrates merely a preferred embodiment of the invention, and that other embodiments are contemplated within the scope of the claims hereafter set out.

Referring to the drawings the card table includes the rectangularly shaped open frame 11 which is formed from tubing of circular cross section which has been drawn to the approximate elliptical shape shown at 11a, Figure 4. In practice the tubular support is formed to a completed rectangle, not shown in the drawing with the free ends suitably secured to each other as by welding.

Each of the four pivotal legs of the table are mounted in the manner illustrated in Figures 2, 3 and 4, there being a separate mounting for each leg, one of which is shown in the drawings for illustration.

Referring to Figures 2, 3 and 4, a leg supporting bracket 12 is secured to the table frame 11 as by the welds 13 and 14, and perhaps the additional welds 15 and 16 if desired for additional rigidity.

Said bracket generally indicated by the numeral 12 includes the parallel spaced inturned leg supporting elements 17 and 18, the central portion 19 and the straight portion 20. The outer edges of the bracket 12—20 are arcuately formed at points 21 for cooperative registry with the corresponding arcuate portions 22 at the top and bottom of the table frame 11.

One end of the bracket 12—20 is formed with the embossment 23 thereon which has an angularly inclined outer surface 24, which as shown in Figure 2 extends towards a corresponding portion of the table frame 11 as shown.

The pivotal table leg 25 is positioned between bracket elements 17 and 18 and is pivotally joined to bracket element 18 by the rivet 26 which extends from said bracket and engages the adjacent inner wall of said leg.

Reinforcing bracket 27 is secured at one end at point 28 to the leg 25 and is so formed as to extend upwardly with its opposite end pivotally joined to bracket element 17 by the rivet 29. By this construction it is apparent that the leg may be pivoted from the position shown in the drawings 90 degrees to the closed position in parallel alignment with the frame 11.

A novel type of linkage is interposed between said frame and an intermediate portion of said leg for guiding the pivotal movements of said leg,

tending to retain said leg frictionally in its closed position, and being so formed as to lockingly retain said leg in its fully open position.

This link 30 is substantially rectangular in shape with its peripheral portions folded over inwardly as at the points 31 to retainingly engage the insert 32 of corresponding shape which is longitudinally and centrally slotted at 33.

As shown in Figure 4 the lower end of the slot 33 terminates in the enlarged circular opening 34, while the opposite end of said slot terminates in another enlarged circular opening 35 of slightly increased diameter.

Link 30 is positioned at its upper end over the inclined surface 24 of embossment 23 and is pivotally joined thereto by the transverse rivet 36. Said rivet extends through corresponding openings in the link 30 and embossment 23 and is secured to the inner surface of said embossment which corresponds to and forms a part of the leg bracket element 20. Naturally the link is riveted to said embossment prior to assembly of the bracket upon and its securing to the table frame 11.

The locking pin which is carried by and secured to the leg 25 and which slidably engages the link 30 within the guide slot 33 has a central portion 37 of such diameter as to be slidable within the link slot 33. The shank 37 terminates in the annular shoulder 38 of slightly increased diameter, and this shoulder terminates at its outer end in the annular shoulder 39 of still slightly increased diameter.

The diameter of shoulder 39 is such that the same may be inserted within the enlarged circular opening 35 at one end of the slot 33. The hollow interior portion 40 of the link 30 is of such depth as to permit complete entry of the annular shoulder 38 therein whereby the shank 37 may be slid longitudinally of the link slot 33.

The annular shoulder 38 is of such diameter that it will slide through the circular opening 34 at the opposite end of slot 33 and when so positioned the leg 25 will be retained in its completely open position as in Figure 6.

The shank 37 terminates in the portion 41 of a diameter less than the diameter of shank 37 providing the shoulder 42. The portion 41 of said locking pin as shown in Figure 3 is projected through corresponding openings formed in the leg 25 with the shoulder 42 retainingly engaging said leg on one side thereof and with the outer portion of said pin 41 extending through a corresponding opening in the lower end of bracket 21, being riveted thereto at point 28.

By this construction it is apparent that the locking pin 37-41 is effectively secured to the leg 25 for movement therewith. Furthermore, in any intermediate positions of pivotal adjustment of said leg, the link 30 as viewed in Figure 3 must be pushed to the left as indicated by the arrow so that the annular shoulder 38 is entirely within the slot 40 of said link. When so positioned, it is possible to pivot the leg upwardly into the frame with shoulder 38 riding within the interior portion 40 of said link with the outer surface of shoulder 38 slidably engaging the inner surface of the slotted element 32, as shown in Figures 7 and 8.

In the outer position of said leg when fully open, the shoulder 38 is retainingly received within the circular opening 34 of slot 33 and at the same time the annular shoulder 39 retainingly engages the slotted element 32 so that said pin may not be withdrawn therefrom.

In view of the inclined surface 24 of boss 23 to which the link 30 is pivoted, it is clear that said link will normally assume the position shown in Figure 3 which is at a slight inclination to the leg 25. Consequently in order to release the shoulder 38 from the opening 34 of said link, it is necessary to manually press the lower end of link 30 inwardly towards the leg 25 until the relative position of the shoulder 38 and said link is such that the shank 37 is free to slide within the slot 33.

Under this condition it is apparent that the link 30 will be under tension throughout the period that the shank 37 is sliding relative to the slot 33 as the leg is pivotally closed relative to the frame 11. By this construction it is clear that an additional friction relationship is established which will tend to retain said leg in closed position.

Consequently in all positions of the leg 25 other than the fully open normal position shown in the drawings, said link 30 will be under tension. This is due to the fact that the upper end of said link is pivotally mounted upon the inclined surface 24 of the boss 23 which forms a part of the bracket 12-20. In view of the pivotal connection 36, the inner surface of the link 30 is in cooperative registry with the tapered surface 24 of boss 23 so that normally said link will be bent outwardly at its lower end out of parallel relation with the corresponding portion of the frame to which its upper end is pivotally joined.

It follows further that the link 30 will be at all times under this tension until the leg 25 has been pivoted to the fully open position shown in Figure 3, at which point annular shoulder 38 will be in registry with the locking opening 34 so that said link 30 will resiliently snap outwardly in the manner illustrated in Figures 3 and 6.

In operation the table legs are opened merely by pivoting the same outwardly, there being nothing to release inasmuch as in any position of the leg other than fully opened position the aforesaid annular shoulder 38 bears against the inner surface of the insert 32 adjacent the slot 33, as illustrated in Figures 7 and 8. When the leg is fully opened link 30 with circular recess 34 will snap outwardly into locking position relative to shoulder 38 on locking pin 37. To release the leg it is merely necessary to press the lower end of link 30 inwardly slightly until the shoulder 38 is fully outside of recess 34, i. e. to the position shown in Figure 8. After this the leg may be freely pivoted to the fully closed position.

A slightly different arrangement of the pivotal support for the leg 25 is shown in Figure 1 in which the rivet 43 pivotally supports said leg with one end of said rivet extending through the portion 19 of bracket 12, and with the opposite end of said rivet extending through the outer portion of bracket element 17, being secured thereto at point 44.

To complete this construction the cylindrical spacer 45 is mounted upon said rivet with its ends interposed between leg 25 and the inner surface of the bracket element 17, to thereby maintain the leg in the position shown relative to said rivet.

In all other respects the embodiment shown in Figure 1 is the same as the embodiment shown in Figures 2 through 8.

A cover of substantially rectangular shape i. e. element 46, is positioned over the rectangular frame work 11 with the outer peripheral por-

tions 46' of said cover extending to approximately the central top portion of frame 11.

A plurality of table top securing angle elements 47 are riveted at 48 to the under surface of table top 46, with the downwardly depending portions of said angle elements being respectively secured at spaced points to the inner walls of the frame 11 as by the screws 49.

Having described my invention reference should now be had to the claims which follow for determining the scope thereof.

I claim:

1. In a table construction, a leg pivotally joined thereto, a hollow elongated housing pivotally joined at one end to said frame in non-parallel relation thereto, a centrally slotted leg engaging link for said leg nested and secured within said housing, there being a locking recess at one end of the slot in said link, a locking pin projecting from said leg into said housing and through said slot for sliding engagement relatively thereto, an annular shoulder adjacent the outer end of said pin normally positioned within said housing and slidably engageable with the inner surface of said link, said shoulder being retainingly engageable within said recess when said leg is pivoted to fully open position, a second annular shoulder of increased diameter upon the outer end of said pin and nested within said housing, with the outer surface of said latter shoulder slidably engaging the inner surface of said link when said leg is in fully open position.

2. In a table construction having a frame, a leg pivotally joined thereto, a boss on said frame having a slightly inclined surface with respect to said frame, a hollow elongated housing bearing upon said inclined surface at one end and

10
15

20

25

pivots joined to said frame in non-parallel relation thereto, a centrally slotted leg engaging link for said leg nested and secured within said housing, there being a locking recess at one end of the slot in said link, a locking pin projecting from said leg into said housing and through said slot for sliding engagement relatively thereto, an annular shoulder adjacent the outer end of said pin normally positioned within said housing and slidably engageable with the inner surface of said link, said shoulder being retainingly engageable within said recess when said leg is pivoted to fully open position, a second annular shoulder of increased diameter upon the outer end of said pin and nested within said housing, with the outer surface of said latter shoulder slidably engaging the inner surface of said housing during opening of said leg, and with the inner portion of said latter shoulder retainingly engaging the inner surface of said link when said leg is in fully open position.
